UNITED STATES PATENT OFFICE.

GEORGE W. KENNEDY, OF DELAWARE CITY, DELAWARE.

WINDOW-VENTILATOR.

No. 880,538.

Specification of Letters Patent.

Patented March 3, 1908.

Application filed March 29, 1907. Serial No. 365,350.

To all whom it may concern:

Be it known that I, GEORGE W. KENNEDY, citizen of the United States, residing at 5 Delaware City, in the county of Newcastle and State of Delaware, have invented certain new and useful Improvements in Window-Ventilators, of which the following is a specification.

The present invention relates to certain new 10 and useful improvements in window ventilators, the object being to provide a simple device of this character embodying a novel construction whereby an air deflecting slat can be adjustably mounted between a pair 15 of oppositely disposed end plates and held at fixed angles as may be required by various conditions.

A further object of the invention is to so 20 design the window ventilator that it can be readily applied to any of the conventional types of window frames without in any manner defacing or altering the same.

For a full description of the invention and the merits thereof and also to acquire a 25 knowledge of the details of construction and the means for effecting the result, reference is to be had to the following description and accompanying drawings, in which:

Figure 1 is a perspective view of a portion 30 of a window frame having the ventilator applied thereto. Fig. 2 is a vertical sectional view through the same. Fig. 3 is a similar view showing the ventilating slats as folded against each other and forming a 35 vertical barrier. Fig. 4 is also a similar view showing the ventilating slats in inoperative position. Fig. 5 is a horizontal sectional view through the window frame. Fig. 6 is a front elevation of one corner of a window 40 frame and shows a modified form of end plate. Fig. 7 is a detail view of the modified form of end plate shown in Fig. 6. Fig. 8 is a perspective view showing a modified construction of the deflecting slats. Fig. 9 is 45 a plan view of a further modification of the end plates. Fig. 10 is a perspective view of an embodiment of the invention wherein the deflecting strips are provided with retractable tongues. Fig. 11 is a detail view of a 50 modification.

Corresponding and like parts are referred to in the following description and indicated in all the views of the drawings by the same reference characters.

In its broadest phase the invention comprises essentially an air deflecting slat ex-

tending transversely across the window frame, and side plates carried by opposite sides of the window frame, the said air deflecting slat and side plates having a tongue 60 and socket connection whereby the slat can be held in any one of a series of positions as may be found desirable.

In the form of the invention shown in Fig. 1 the air deflecting slat 1 is shown as provided at its opposite ends with the longitudinally disposed lugs 2 which are located adjacent one of the longitudinal edges thereof and are designed to engage any one of a series of sockets or notches formed in the end 70 plates 3 and secured to the window jambs on opposite sides of the frame. In the specific construction of the end plates 3 it will be observed that the same are formed with a pair of vertically disposed sockets or notches 75 4 and 5 extending downwardly from the upper edge thereof and the socket 5 being deeper than the socket 4 and located nearer to the rear edge of the plate. Below the socket 5 and inclining downwardly from the 80 rear edge of the plate is an intermediate socket 6, and toward the lower portion of the plate is a horizontally disposed socket 7 having an inclined socket 8 in communication therewith. As shown in Fig. 1 it will also 85 be observed that a second air deflecting slat 9 may be employed which has one of its longitudinal edges hinged or loosely connected to a corresponding edge of the slat 1 in any suitable manner so as to fall against the same 90 and have a swinging motion with relation thereto. It will be noted that the lugs 2 have an angular formation and that the sockets correspond in shape to the same, thereby enabling an interlocking connection 95 to be produced between the said tongues and sockets for locking the deflecting slat 1 in an adjusted position and preventing any swinging movement of the same. When the lugs 2 are positioned within the sockets 4 of the 100 side plates 3 in such a manner that the air deflecting slat 1 extends vertically upwards, the slat 9 is pendent from the lower edge thereof and is inclined forwardly at an angle so as to deflect upwardly any air which might 105 enter were the lower window sash slightly elevated. However should the air deflecting slat 1 extend downwardly when the lugs 2 are received by the sockets 4, the slat 9 will fall against the slat 1 to produce a vertical 110 barrier against direct currents of air as indicated in Fig. 3. When the lugs 2 are engaged

by the sockets 5 the deflecting slats are held in a position similar to that described, the essential difference residing in the fact that the pendent slat 9, the lower edge of which 5 rests upon the window sill, is disposed at a greater angle from the vertical. Should the lugs 2 be placed within the intermediate inclined socket 6 both of the air deflecting slats 1 and 9 will be inclined, a similar condition 10 will exist when the lugs 2 engage the lower inclined sockets 8, except that in the latter instance the two plates will be inclined at a greater angle to the vertical and will not offer as effective a barrier to a direct current of 15 air entering through the window. When the slats are not in position they can be folded against each other so as to rest upon the window sill as shown in Fig. 4, the lugs or tongues 2 being received by the horizontal 20 sockets 7.

The air deflecting slats 9 and 1 may be formed of any suitable material and may either comprise a pair of wooden strips, or a pair of metallic strips having their adjacent 25 longitudinal edges loosely connected so as to have a swinging movement with respect to each other. Under some conditions it may be found desirable to cut away or bevel the lower edge of the pendent air deflecting slat 30 9 as indicated at 10,

In Fig. 8 a slight modification is shown in which the pendent air deflecting slat 9^a is shown as formed of sheet metal and is provided at its lower edge with a laterally extended flange 11 designed to fit over the window sill in order to prevent any air from finding its way under the air deflecting slat. Any suitable mechanical means may be employed for providing the tongues 2 at opposite ends 35 40 of the air deflecting slat 1, and in the present instance the said tongues are shown as formed in connection with plates 12 which are secured to the said slat 1.

The side plates 3 are preferably secured 45 along their outer edges to strips 13 extending along the portion of the window jamb adjacent the sash, and with this construction the notched or socket portions of the plates are held in a spaced position from the window 50 jamb, thereby affording a clearance space for the operation of the tongues 2 which effectively prevents any binding of the latter. However should the window frame not be provided with the strips 13 a modification 55 may be employed similar to that shown in Fig. 9 in which the end plate 3 has the rear edge thereof secured directly to the window jamb and is provided with an offset portion 14 which throws the body portion of the end plate away from the window jamb and provides the desired clearance space. Should the sill of the window frame not be of a sufficient depth to form a support for the deflecting slats when folded together and held in an 60 65 inoperative position with the tongues 2 in

the horizontal sockets 7, the lower edge of the plates 3 may be formed with the inwardly extending ledges 15 designed to serve as a support for the said air deflecting slats.

A still further modification is shown in Fig. 70 10 in which the end plates 3^b are formed with a series of sockets 16 which are in the nature of openings formed in the said plates. In this instance the tongue 2^b mounted upon the air deflecting slat 1^b is retractable and is 75 provided with a finger-piece 17 by means of which it can be readily withdrawn from any one of the openings or sockets 16. It is also within the province of the invention to form the end plates with tongues and to provide 80 the air deflecting slat with sockets engaging the tongue. In Fig. 11 the end plates 3^c are formed along their rear edge portion with a series of tongues 18 disposed at different 85 angles and positions with relation to each other, and the air deflecting slat 1^c carries socket pieces 19 at opposite ends thereof designed to engage with a selected pair of the tongues 18 to hold the air deflecting slat at 90 the required angle.

Having thus described the invention, what is claimed as new is:

1. In a window ventilator, the combination of oppositely disposed side plates, an air deflecting slat adjustably supported between the side plates, a tongue and socket connection being provided between the side plates and deflecting slat and the said tongues and sockets being of angular formation and adapted to interlock with each other to hold 100 the deflecting slat in an adjusted position, and a second air deflecting slat hinged to one of the longitudinal edges of the first mentioned air deflecting slat and designed to be folded against the same in either a vertical 105 or horizontal position or to hang at an angle to the same.

2. In a window ventilator, the combination of oppositely disposed side plates provided with a series of corresponding sockets 110 of angular formation, and a pair of air deflecting slats having the longitudinal edges thereof hinged, one of said slats having angular tongues projecting from the opposite ends thereof adjacent the edge to which the opposite slat is hinged, the said tongues being adapted to interlock with a selected pair of the corresponding sockets in the side plates to hold the deflecting slats in an adjusted position.

3. In a window ventilator, the combination of a pair of side plates each of which is provided in its upper edge with a pair of vertical sockets one of which is deeper than the other, and also at its rear edge with an inclined socket and a horizontal socket, an air deflecting slat provided at its extremities with angular tongues designed to interlock with a selected pair of the sockets to hold the air deflecting slat in an adjusted position, and 125 130

a second air deflecting slat hinged to the first mentioned slat and designed to hang therefrom at an angle varying according to the sockets engaged by the tongues of the first mentioned slat.

4. In a window ventilator, the combination of oppositely disposed side plates, an air deflecting slat adjustably supported between the side plates, and a second air deflecting slat hinged to one of the longitudinal edges of the first mentioned slat, the second mentioned slat being provided at its free edge with a laterally extended flange for the purpose specified.

5. In a window ventilator, the combination of oppositely disposed side plates pro-

vided with a plurality of corresponding sockets of angular formation, an air deflecting slat mounted between the side plates, and retractable tongues carried by opposite ends of the deflecting slat, the said retractable tongues being of angular formation and adapted to interlock with any selected pair of the before mentioned sockets to hold the deflecting slat in an adjusted position. 20

In testimony whereof I affix my signature in presence of two witnesses.
